UNITED STATES PATENT OFFICE.

BENJAMIN F. LINDLEY, OF DANVILLE, ILLINOIS.

RAIL-JOINT.

1,168,520.

Specification of Letters Patent.

Patented Jan. 18, 1916.

Application filed July 7, 1915. Serial No. 38,403.

To all whom it may concern:

Be it known that I, BENJAMIN F. LINDLEY, a citizen of the United States, residing at Danville, in the county of Vermilion and State of Illinois, have invented certain new and useful Improvements in Rail-Joints; and I do hereby declare the following to be a full, clear, and exact description of the invention, such as will enable others skilled in the art to which it appertains to make and use the same.

My invention relates to new and useful improvements in rail joints and my object is to provide means for joining the meeting ends of the rails in such manner as to render the joint of substantially the same strength as the remaining portion of the rail.

A further object is to so construct the parts that the jar received in passing over the joints of the rails will be eliminated. And a further object is to provide means for securing the parts employed for securing the rails together, to the tie in such manner as to prevent spreading or disalignment of the rails.

Other objects and advantages will be hereinafter set forth and more particularly pointed out in the accompanying specification.

In the accompanying drawings which are made a part of this application, Figure 1 is a side elevation of the meeting ends of the two rails showing the parts employed for securing the same together. Fig. 2 is a top plan view thereof. Fig. 3 is a sectional view as seen on line 3, 3 Fig. 1, and Fig. 4 is a sectional view as seen on line 4, 4 Fig. 1.

Referring to the drawings in which similar reference numerals designate corresponding parts throughout the several views, 1 and 2 indicate the meeting ends of rails such as are employed for forming a track for railway trains, street cars and similarly operated vehicles.

The rails have a portion of their heads 3 and 4 removed on each side to provide tongues 5 and 6, which tongues are in width equal to the width of the webs 7 and 8 of the rails. The ends 9 and 10 are under cut to dispose the same at an angle with which ends coöperate the angular faces 11 and 12 respectively of the head forming extensions 13, which extensions are carried by angle bars 14, the width of the extensions 13 being coincident with the width of the heads 3 and 4 on opposite sides of the tongues 5 and 6,

thus retaining the head of uniform width at the meeting ends of the rails and at the same time breaking the joint so that the jar incident to the wheels passing over the joint will be eliminated.

The angle bars 14 extend a distance on each side of the meeting ends of the rails and have their upper edges in engagement with the under faces of the heads of the rails 15 and are secured to the rails by means of bolts 16 which pass transversely through the angle bars and the web of the rails, the inner faces of the angle bars having concavities 17 therein so as to give a slight yielding action to the angle bars when the bolts are drawn taut, thus wedging the upper and lower edges of the angle bars between the head and base 18 of the rails.

The foot portion 18 of the angle bars extends over the upper face of the base 19 and is provided with a depending flange 19 which extends over the edges of the base and a distance below the base so that the lowermost edge of the flange will engage the tie 20 and between that portion of the depending flange of the two plates below the base of the rail is a base plate 21, said plate extending the full length of the angle bars, thus bracing the rails at the joints to such an extent that the joints can be disposed between ties if necessary.

The extensions 13 are securely locked in the cavities formed by removing portions of the heads of the rails, by introducing a locking bolt 22 transversely through said extensions and at the point of juncture between the tongues 5 and 6, the faces of said tongues having semi-circular recesses 23 to receive the locking bolt, and to obviate any possibility of the flange of the wheel engaging the head of the bolt, said head is always placed at the inner face of the rail and countersunk into the extensions 13. The locking bolt 22 is positioned in a plane above the bolts 15 so as to positively lock the extension in engagement with the tongues of the rails.

The rails are secured to the ties by introducing spikes 24 through slots 25 in the foot portion 18 of the angle bar and through notches 26 and 27 in the edges of the base 17 and base plate 21 and as the upper portions of the spikes are surrounded by metal, it will be impossible for the spikes to give to permit spreading of the rails.

It will thus be seen that I have provided

means for securing the meeting ends of the rails together in such manner that the rails will be as strong at their point of joining as at any other point of the rail and furthermore that by providing the extension on the angle bars and extending them on opposite sides of the meeting portions of the rails, the jar incident to the wheels passing over the joints will be entirely eliminated and the rails provided with a uniform upper surface. It will further be seen that this device can be very cheaply constructed and readily applied to use and by fastening the spikes to the base of the rail as shown, it will be impossible for the rails to separate.

Having thus fully described my invention what I claim as new and desire to secure by Letters Patent is:—

1. In a rail joint, the combination with the meeting ends of rails, each end having a portion of its head removed on opposite sides of the web of the rail to form tongues, of angle bars having extensions at their central portion adapted to occupy the spaces formed by removing portions of the rail heads, said extensions projecting on opposite sides of the joint between the rails, a bolt extending transversely through the extensions and between the ends of the tongues, said tongues having recesses to receive the bolt, the head of said bolt being flush with the face of the extension on the inner face of the rails, a foot portion for each angle bar extending over the base of the rail and having a flange extending downwardly over the edge of the base and a distance below the same, said foot portion having a slot therein, a base plate below the rails, said base and base plate having notches registering with the slots of the foot

portion, and spikes adapted to extend downwardly through said slots and notches and into a tie.

2. In a rail joint, the combination with the meeting ends of rails having portions of the heads removed to form tongues, the width of said tongues being equal to the width of the web of the rail, said tongues having semi-circular recesses in their meeting ends, the ends of the heads being undercut, of angle bars having upwardly extending extensions at their longitudinal center, the end faces of the extensions being extended at an angle to fit the angle of the under-cut ends of the heads of the rails, a bolt extending transversely through the extensions and through the opening formed by the semi-circular recesses in the tongues, bolts extending transversely through the angle bars and the interposed rail webs and in a plane below the bolt in the extensions, foot portions at the lower edges of the angle plates extending over the faces of the base of the rail, said portions having slots therein, said foot portions terminating in depending flanges, and a base plate between said depending flanges and below the base of the rail, said base and base plate having notches registering with the slots in the foot portion, and spikes adapted to be entered through said registering slots and notches and into a tie.

In testimony whereof I have signed my name to this specification in the presence of two subscribing witnesses.

BENJAMIN F. LINDLEY.
